COMBINATION ASH TRAY AND SIGNAL

Richard T. Cornelius, Minneapolis, Minn.

Application March 19, 1949, Serial No. 1,488

Term of patent 7 years

(Cl. D85—2)

To all whom it may concern:

Be it known that I, Richard T. Cornelius, a citizen of the United States, residing at Minneapolis, county of Hennepin, and State of Minnesota, have invented a new, original, and ornamental Design for a Combination Ash Tray and Signal, of which the following is a specification, reference being had to the accompanying drawing, forming a part thereof.

In the drawing:

Fig. 1 is a perspective view of a combination ash tray and signal, illustrating my new design.

Fig. 2 is a side elevational view of the design shown in Fig. 1.

Fig. 3 is a plan view of the design shown in Fig. 1.

I claim:

The ornamental design for a combination ash tray and signal, as shown.

RICHARD T. CORNELIUS.
